FIG. 1 is a front, top, right perspective view of a second example of the radiused insert of the new design;
FIG. 2 is a top plan view thereof;
FIG. 3 is a cross-sectional view along line 3-3 of FIG. 2;
FIG. 4 is a left side view thereof, the right side being a mirror image thereof;

FIG. 5 is a front side view thereof; and,

FIG. 6 is a bottom plan view thereof.

The broken line showing of environment in the drawings is for illustrative purposes only and forms no part of the claimed design.
